UNITED STATES PATENT OFFICE.

DANIEL H. MUIR, OF LINCOLN, NEBRASKA.

GASOLENE-ENGINE.

1,055,069.

Specification of Letters Patent.

Patented Mar. 4, 1913.

Application filed June 20, 1911. Serial No. 634,351.

To all whom it may concern:

Be it known that I, DANIEL H. MUIR, residing at Lincoln, county of Lancaster, State of Nebraska, a citizen of the United States, have invented certain new and useful Improvements in Gasolene-Engines; and I do hereby declare the following to be a full, clear, and exact description of the invention, such as will enable others skilled in the art to which it pertains to make and use the same.

My invention relates to improvements in gasoline engines.

It has for its object the placing of an air tight packing for the piston, which separates the gas of the combustion chamber from the outside air, at a point where said packing will not be affected by the heat generated in the combustion chambers and will be capable of being cooled without affecting the combustion chamber.

It also has for its object to provide means for preventing the lubricant used to lubricate the engine from being heated.

It further has for its object to cool the several parts of the engine by atmospheric air, water or other cooling medium.

It still further has for its object to provide an engine of the character described which is simple, inexpensive, durable and compact in construction and easily operated.

The invention consists in the features and combination of features as hereinafter described and claimed.

Referring to the drawings:—Figure 1 is a top plan view in elevation. Fig. 2, a central vertical section. Fig. 3, an end view. Fig. 4, a cross-section on the line $w-w$ of Fig. 2. Fig. 5, a detail section of the piston. Fig. 6, a section of a modified form of my invention. Fig. 7, a cross-section on line $y-y$ of Fig. 6. Fig. 8, a section of a modified form of my invention applied to a vertical type of engine.

In the drawings in which similar reference characters denote corresponding parts throughout the several views, 1 indicates the outer cylinder of my engine which is preferably made in two sections 2 and 3 secured together by means of bolts 4 passing through the flanges 5 of each section.

The left hand end of the outer cylinder 1

is provided with a flange 6 to which is secured by means of bolts 7 a cylinder head 8 having an inlet pipe 9 and an exhaust pipe 10 therein and a sparking device 11, while the opposite or right hand end of the outer cylinder 1 is provided with a flange 12.

13 indicates the inner cylinder spaced apart from the outer cylinder by having a space 14 between the inner surface of the outer cylinder and the outer surface of the inner cylinder, the inner cylinder being preferably made in two sections 15 and 16 having flanges 17 secured together by means of bolts 18, and being open to the air at its outer end 19 and having a flange 20 at its outer end which is secured to the flange 12 on the adjacent end of the outer cylinder by means of bolts 21, and said inner cylinder 13 having a cylinder head 22 at its inner end with inlet pipe 23, exhaust pipe 24, sparking device 25 and a central sleeve 26 supported within said cylinder by means of a depending bracket 27.

The piston 28 is provided with a piston head 29, having a piston rod 30, which passes through the sleeve 26 of the inner cylinder 13 and packing box 26^a, and a flange 31, said flange 31 being slidably mounted in the space 14 between the outer and inner cylinders so as to fit closely therein and adapted to be lubricated by oil or other lubricant in any desired manner. An explosion chamber 33 is formed between the cylinder head 8 of the outer cylinder 1 and an explosion chamber 34 is formed in the interior of the piston, between the piston head 29 and the cylinder head 22 of the inner cylinder 13.

All the joints will be made air tight by means of any suitable well known packing material 35, except the joints at the points 35^a, between the piston flange and the inner and outer cylinders, which joints will be rendered absolutely air tight by means of spring packing rings 35^b seated in grooves in rings 35^c and suitable soft packing 35^d on either side of said rings 35^c. The above joints may, if desired, be made air tight by any other means.

It will be noted that by placing the air tight packing which consists of packing rings 35^b at the point 35^a, remote from the

combustion chambers, they will not be affected by the heat generated in said chambers and at the same time can be cooled in any desired manner without affecting the 5 temperature of the said combustion chambers.

The inlet and exhaust pipes of the inner and outer cylinders will be provided with suitable valves, not shown.

10 The piston flange is preferably made of light thin steel, but of course may be made of any suitable material, and as said before is designed to fit closely in the space 14, but not so closely as to prevent the expansion 15 and contraction of the same. As the outer surface of the outer cylinder is exposed to the air at all times and as the inner surface of the inner cylinder and the sleeve are exposed to the air at all times, by reason of 20 the outer end of the inner cylinder being open to the air, it will be readily seen that the several parts of the engine will be cooled and prevent the lubricant from being wasted 25 or destroyed by excessive heat.

30 In the modified form of my invention shown in Fig. 6, the outer cylinder is indicated at 36 and is provided with a cylinder head 37 at one end having inlet and exhaust pipes and a framework 38 at the opposite 35 end. The inner cylinder 39 which is spaced apart from the outer cylinder by means of a space 40, is open to the air at its outer end and also connected to the framework 38 and its inner end is provided with inlet and 40 exhaust pipes.

45 The piston 41 is provided with a piston rod 42, piston head 43 and a flange 44, said flange being slidably mounted in the space 40 between the cylinders 36 and 39 and designed to be projected beyond the ends of 50 the said cylinders and cooled by the air at each stroke of the piston.

55 In Fig. 8, a modified form of my invention is shown applied to a vertical type of engine, in which all the parts are similar to the parts shown in Fig. 6 except that the piston rod extends upward from the piston and a receptacle 45 is provided within the framework 38 for containing water or other 60 cooling medium into which the flange of the piston is adapted to be projected and cooled at each stroke of the piston.

It will be seen that by my invention the several parts may be kept cool by air, water, 65 or any other suitable cooling medium.

The operation of the engine is so obvious that it is not thought necessary to describe it.

70 I do not wish to be understood as limiting myself to the details of construction and arrangement as herein described and illustrated, as it is manifest that variations and modifications may be made in the features of construction and arrangement in the

adaptation of the device to various conditions of use without departing from the spirit and scope of my invention and improvements. I therefore reserve the right to all such variations and modifications as properly fall within the scope of my invention and the terms of the following claims.

What I claim is:—

1. In a gasoline engine, inner and outer cylinders having a space between them, the inner cylinder being open to the air at its 75 outer end, and a piston slidably mounted in the space between said cylinders and its outer end adapted to be projected out of the said space for the purpose of being cooled at each stroke of the said piston, substantially as described.

2. In a gasoline engine, inner and outer cylinders spaced apart, a receptacle for containing a cooling medium connected to said cylinders, and a piston slidably mounted in 85 the space between the cylinders and adapted to be projected into said receptacle and cooled at each stroke of the same, substantially as described.

3. In a gasoline engine, inner and outer cylinders spaced apart, a receptacle for containing a cooling medium connected to said cylinders, the inner cylinder being open to the air at its outer end and having inlet and exhaust ports, the outer cylinder having an 95 explosion chamber and inlet and exhaust ports, and a piston having a flange slidably mounted in the space between the cylinders and an explosion chamber, said flange adapted to be projected into said receptacle 100 containing the cooling medium and cooled at each stroke of the piston, substantially as described.

4. In a gasoline engine, inner and outer cylinders spaced apart, a receptacle for containing a cooling medium connected to the lower ends of said cylinders, the inner cylinder being open to the air at its lower end and having inlet and exhaust ports in its upper end, the outer cylinder having inlet 110 and exhaust ports in its upper end and an explosion chamber, and a piston containing an explosion chamber and having a flange slidably mounted in the space between the said cylinders, said flange adapted to be projected into the receptacle containing the cooling medium at each stroke of the piston, substantially as described.

5. In a gasoline engine, an inner and outer cylinder provided with inlet and exhaust ports and an explosion chamber in said outer cylinder, a receptacle for containing a cooling medium connected to the outer cylinder and a piston having a flange, inlet and exhaust ports and an explosion chamber, said flange adapted to be projected into 115 said receptacle and cooled at each stroke of the piston, substantially as described.

5. In a gasoline engine, outer and inner cylinders, an explosion chamber in the outer cylinder, stationary packing carried by each of said cylinders, at the opposite end from the explosion chamber, thereof, a piston operatable between said cylinders and between the packing carried thereby and an explosion chamber in said piston at the op-

posite end from the packing of the cylinders, substantially as described. 10

In testimony whereof, I affix my signature in the presence of two witnesses.

DANIEL H. MUIR.
